UNITED STATES PATENT OFFICE.

NELSON FULCHER AND JOHN HERBERT PICKETT, OF SAULT STE. MARIE, ONTARIO,
CANADA.

POUNDER WASHING-MACHINE.

1,139,511.

Specification of Letters Patent. Patented May 18, 1915.

Application filed September 21, 1914. Serial No. 862,693.

To all whom it may concern:

Be it known that we, NELSON FULCHER and JOHN HERBERT PICKETT, both subjects of the King of Great Britain, and residents 5 of Sault Ste. Marie, in the Province of Ontario, Dominion of Canada, have invented certain new and useful Improvements in Pounder Washing-Machines, of which the following is the specification.

10 This invention relates to improvements in vacuum washing machines and the objects of the invention are to provide means for rapidly effecting the washing of a considerable quantity of clothes, to enable a plurality 15 of washing elements to be mechanically operated and arranged to operate uniformly on different parts of the clothes in the tub.

Further objects are to improve and simplify the operating mechanism to cause the 20 washing elements to be alternately raised and lowered and at the same time moved in a circular path within the tub.

Further objects still are to improve the construction of the washing elements to better insure that the washing water is forced 25 through the clothes.

It consists essentially of the improved construction hereinafter described in detail in the accompanying specification and drawings.

In the drawings, Figure 1 is a plan view of an embodiment of the invention. Fig. 2 is a sectional elevation. Fig. 3 is a sectional elevation taken at right angles to Fig. 2. 35 Fig. 4 is a sectional detail through one of the washing elements or pounders.

In the drawings like characters of reference indicate corresponding parts in all the figures.

40 Referring to the drawings, A represents any suitable form of receptacle for the clothes to be washed, such as a tub.

B represents the supporting frame secured to the top of the tub in any suitable way.

45 The form of connection I have illustrated comprises a tub hinge 10 including a bracket 11 secured to the frame B and a hinge clamp 12 adapted to be secured to the tub. On the opposite side of the frame a clamp 13 is provided also, adapted to engage and clamp 50 the edge of the tub.

The frame B is provided at the bottom with a ring 14 from which posts 15 extend

upwardly and are connected at the top by cross bars 16 and 17.

One of the uprights 15 support and journal the driving crank C, the inner end of which is connected to a driving pinion 20 adapted to mesh with an annular gear D, which annular gear carries the washing elements E. These washing elements are each supported from depending arms 21, the upper ends of which are mounted on cranks 22 on a crank shaft 23, the ends of the crank shafts being journaled in posts 24 and 25 60 which are secured to and extend downwardly from the annular gear D, the lower extremities of the posts being connected and strengthened by a cross bar 26.

This cross bar has perforations 26^a 70 through which the supporting arms 21 of the washing members extend and slide. In this way a rocking as well as an up and down motion is given to the washing members.

To provide adjustment of the depth to 75 which the washing element will be forced, the arms 21 are formed in two sections 27 and 28 telescoping together and adapted to be clamped together by a bolt and thumb nut 29.

To cause the crank shaft 23 to be turned when the gear D is turned, a gear F is provided on the crank shaft adapted to mesh with an annular gear G which is fixedly secured to the frame B whereby as the gear F 85 is carried around with the gear D it will be turned with the crank shaft 23 by the gear G, the latter remaining stationary. The gear G also rotatably supports the gear D which latter may be termed the rotary gear, 90 this being accomplished by an annular flange 50 on the gear G which extends into an annular recess 51 on the gear D. Suitable ball bearings 52 may be provided between the rotary gear and the cross bars 16 and 17. In 95 this way the washing elements will be reciprocated up and down and also moved in a circular path on the inside of the tub, while seldom striking in the same place.

Additional support may be given to the 100 frame B by means of a suitable brace 40 which may extend to any suitable support, when the machine is turned on hinge 10.

The construction of the washing elements E is shown in Fig. 4. Each is conical in 105 form and provided with a partition 30 near

the top, formed with a central perforation 31, the upper side of which forms a seat for the ball 32. The ball itself is supported in a tube 33 which forms an extension of the 5 arm 21.

The tube 33 is formed with perforations 34 through which the water may flow and the portion of the conical member above the partition is also formed with perforations 35.

10 To provide for cleaning of the interior of the upper end of the conical member a sliding door 36 is provided in the side thereof.

15 It may be stated that the construction of the washing member or pounder is novel in itself and it might be used without the operating mechanism if desired.

20 In operation, the clothes to be washed are placed in a tub of hot water and the vacuum washer worked upwardly and downwardly 25 in a pounding action on the clothes. On the down stroke the water forces the dirt out of the clothes and on the upward stroke the vacuum causes a suction through the clothes which also assists in removing the 30 dirt therefrom.

25 It will be seen that the ball 32 permits water to flow through the conical member on the down stroke, but prevents flowing through it on the up stroke and thereby 30 creates a vacuum on the underside of the conical vacuum member.

35 As many changes could be made in the above construction and many apparently widely different embodiments of my invention, within the scope of the claims, constructed without departing from the spirit or scope thereof, it is intended that all matter contained in the accompanying specification and drawings shall be interpreted as 40 illustrated and not in a limiting sense.

45 What we claim as our invention is:

1. In a washing machine, a stationary frame, a supporting element revolvably depending therefrom, a crank shaft journaled in said supporting element, clothes pounders suspended from said crank shaft, manual means carried by said stationary frame for directly rotating said supporting element, and means whereby the rotation of said element causes said crank shaft to revolve in 50 its journals to operate the pounders.

55 2. In a washing machine and in combination, a supporting member adapted to be clamped to the edge of a tub, an annular gear fixed to the supporting member, a second annular gear supported with freedom

to turn from the supporting member, a crank shaft carried by the annular gear which turns, a gear on the crank shaft meshing with the fixed annular gear, and clothes 60 washing elements carried by the crank shaft.

3. In a washing machine and in combination, a fixed annular gear, a rotary annular gear supported therefrom, means for turning the rotary annular gear, a clothes washing element carried by the rotary annular gear, and means for raising and lowering the clothes washing element operated by the 65 fixed annular gear.

4. In a washing machine and in combination, a fixed annular gear, a rotary annular gear mounted therefrom, a frame carried by the rotary annular gear, a crank shaft mounted in the frame, a gear on the crank shaft meshing with the fixed annular gear, 75 a plurality of clothes washing elements, and means connecting the clothes washing elements with the crank.

5. In a washing machine and in combination, a fixed annular gear, a rotary annular gear mounted therefrom, a frame carried by the rotary annular gear, a crank shaft mounted in the frame, a gear on the crank shaft meshing with the fixed annular gear, 80 a plurality of clothes washing elements, and adjustable means connecting the clothes washing elements with the cranks.

6. A washing machine comprising in combination, a supporting member including a ring, a plurality of uprights, cross bars at 85 the top connecting the uprights, clamps connected to opposite sides of the ring adapted to be clamped to the edge of a pail, an annular gear supported from the cross bars having an annular flange, a rotary annular gear supported on the annular flange, 90 posts extending downwardly from the rotary annular gear, a cross bar connecting the posts, a crank shaft journaled in the posts, a gear on the crank shaft meshing with the fixed gear, washing clothes pounders and arms connecting the clothes pounders with the cranks, substantially as and 95 for the purpose specified.

100 In witness whereof we have hereunto set 105 our hands in the presence of two witnesses.

NELSON FULCHER.
JOHN HERBERT PICKETT.
